[57] **CLAIM**

The ornamental design for the storage container for a pickup or the like, as shown and described.

DESCRIPTION

FIG. 1 is a front elevational view of a container showing my new design.

FIG. 2 is a rear elevational view of the container shown in FIG. 1.

FIG. 3 is a partial front elevational view of the container shown in FIG. 1.

FIG. 4 is a side elevational view of the container shown in FIG. 1, the opposite side elevational view being a mirror image thereof.

FIG. 5 is a cross-sectional view taken along line 5—5 in FIG. 3.

FIG. 6 is a cross-sectional view taken along line 6—6 in FIG. 3.
